PAPER FASTENER

Henry Hellman, Syracuse, N. Y.

Application April 30, 1934, Serial No. 723,126

8 Claims. (Cl. 24—153)

This invention relates to paper fasteners of the type including a base plate with prongs for entering the bundle of papers to be fastened and a compressor plate overlying the top or cover sheet 5 of the bundle and having guides, as slots, through which the prongs extend; and has for its object a paper fastener in which the prongs when bent down on the compressor plate are held in their bent down or clinched position on the compressor 10 plate or released by a bodily shifting movement of the compressor plate toward or from the prongs, a locking means self-contained with, and a part of the compressor plate movable into a locked position by the bodily movement of the 15 compressor plate.

It further has for its object in a paper fastener of this type locking means including a portion or a shoulder movable into position to lock in contradistinction to frictionally hold, or to obstruct relative shifting of the compressor plate and tongues when the tongues are in interlocked engagement with the compressor plate.

The invention consists in the novel features and in the combinations and constructions hereinafter set forth and claimed.

In describing this invention, reference is had to the accompanying drawing in which like characters designate corresponding parts in all the views.

30 Figure 1 is a fragmentary plan view of this paper fastener applied to a bundle of papers.

Figure 2 is a view similar to Figure 1, partly broken away and with the prongs in their position assumed when in upright position and showing 35 the tongues or locking means.

Figure 3 is a sectional view on line 3—3, Figure 1.

Figure 4 is a sectional view on line 4—4, Figure 3.

40 This paper fastening includes generally a base plate having upwardly extending prongs for piercing or entering the bundle of papers to be fastened and a compressor plate having transverse guides, as slots, coacting with the prongs, the prongs being bendable toward each other 45 down on the compressor plate, and the compressor plate having means, as overhanging lips, along one of its longitudinal edges, and preferably for the reasons hereinafter set forth, along both 50 edges, for interlocking with the bent down prongs upon bodily shifting of the compressor plate toward the prongs, after the prongs are bent down on the plate, and unlocking therefrom upon a bodily movement in the reverse direction, and means on the base plate or self-contained there-

with and fixed thereto, movable into interlocking engagement as distinguished from frictional engagement, with the bent down prongs upon bodily movement of the compressor plate to interlock the bent down prongs with the means or lip on the compressor plate.

1 designates the base plate which is formed with prongs 2, the opposite ends thereof for piercing or passing through punched holes in the bundle of papers P to be fastened. 3 designates the compressor plate formed with guides for receiving the prongs, these guides being in the form of transverse slots 4 near the ends of the compressor plate, the slots being of sufficient length to permit a rectilinear bodily shifting movement of the compressor plate forward and from the prongs. The compressor plate is provided, preferably along both edges thereof, with overhanging lips 5, 6, and preferably, the ends of these overhanging lips are bent down as at 7 at their ends onto the compressor plate, these lips constituting means for interlocking with the bent down prongs upon shifting of the plate toward the prongs, after the prongs are bent down on to the plate.

25 In Figures 1 and 3, the prongs are shown as interlocked with the lip 5 of the compressor plate.

The locking means for holding the compressor plate from shifting movement when the prongs are interlocked with the lip 5 and positively holding the prongs in their inter-engaged position with the compressor plate, as distinguished from a frictional locking means, comprises tongues 8 struck from the compressor plate and extending lengthwise thereof between the lips 5, 6, each having a portion 9 at its free end movable behind the adjacent prong 2 when it is locked with the lip 5 of the compressor plate. The tongues are resilient and tend to press upwardly out of the plane of the compressor plate. As here shown, 30 the tongues are provided with a wider base portion, and the shoulder or portion 9 which interlocks with the prongs when bent down, is narrower than the base portion, so that when the prongs are inter-engaged with the lip 5, they are 35 also subject to the upward pressure of the tongues 8 applied thereto through the wider base portions of the tongues.

40 In operation, after the compressor plate has been applied to the prongs, which have been 45 passed through the papers, the prongs are bent down toward each other onto the base plate between the lips 5, 6, and overlies the tongues 8 including the narrower portion 9 thereof. The compressor plate 3 is then shifted bodily up- 50

wardly (Figures 1, 2), so that the lip 5 is carried in position to overhang the prongs 2 and hold them in their bent down position. During this movement the portions 9 of the tongues are carried out from under the prongs 2 and flexed upwardly into interlocking engagement with the edges of the prongs (Figure 1), and thus prevent retrograde shifting movement of the compressor plate when the prongs are locked. To release the prongs for the purpose of removing or adding papers, the tongues 8 or the end portions 9 thereof are compressed by the ends of the fore-fingers of the hand to below the level of the prongs 2 and the compressor plate shifted downwardly to move the lip 5 out of engagement with the prongs 2 and move the end portions 9 of the tongues out from under the prongs, so that the prongs can now be bent upwardly or straightened to permit the removal of the compressor plate, and the addition or removal of papers. The operator may move the compressor plate downwardly to interlock the prongs 2 with the overhanging lip 6, in which case, the end portions 9 of the tongues 8 will remain under the prongs, when the prongs are interlocked with the lip 5, and exert an upward pressure thereagainst, tending to frictionally hold the compressor plate from shifting. Also, when the prongs are interlocked with the lip 5 with the end portions 9 of the tongues obstructing relative shifting movement of the prongs and the compressor plate, the wider base portions 8 of the tongues also exert an upward pressure against the prongs.

By this construction, a paper fastener of this type is provided with positive locking means, as distinguished from frictional locking means at practically no additional cost.

What I claim is:

1. A paper fastener including a base plate having upwardly extending prongs for entering the papers to be fastened, a compressor plate having transverse guides coacting with the prongs, the prongs being bendable toward each other down on the compressor plate and the compressor plate having means along one of its longitudinal edges for interlocking with the bent down prongs upon shifting movement of the plate toward the prongs after the prongs are bent down onto the plate, and locking means on the plate movable into engagement with the prongs to hold them in interlocking position upon shifting movement of the compressor plate into locking engagement with the prongs.

2. A paper fastener including a base plate having upwardly extending prongs for entering the papers to be fastened and a compressor plate having transverse guides coacting with the prongs, the prongs being bendable toward each other down on the compressor plate and the compressor plate having means along one of its longitudinal edges for interlocking with the bent down prongs upon shifting movement of the plate toward the prongs, after the prongs are bent down, and locking means on the compressor plate underlying the prongs when the prongs are bent down and having portions movable into interlocking engagement with the prongs after the compressor plate is shifted to interlock the first means with the prongs.

3. A paper fastener including a base plate having upwardly extending prongs for entering the papers to be fastened, a compressor plate having transverse guides coacting with the prongs, the prongs being bendable toward each other down on the compressor plate and the compressor plate having means along one of its longitudinal edges

for interlocking with the bent down prongs upon shifting movement of the plate toward the prongs, after the prongs are bent down, and locking means on the compressor plate underlying the prongs when the prongs are bent down, and having portions movable into interlocking engagement with the prongs after the compressor plate is shifted to interlock the first means with the prongs, said locking means including resilient tongues, each having a portion movable into position to obstruct the relative shifting movement of the compressor plate when the prongs are interlocked with the compressor plate.

4. A paper fastener including a base plate having upwardly extending prongs for entering the papers to be fastened, a compressor plate having transverse guides coacting with the prongs, the prongs being bendable toward each other down on the compressor plate and the compressor plate having means along one of its longitudinal edges for interlocking with the bent down prongs upon shifting movement of the plate toward the prongs, after the prongs are bent down, the compressor plate having resilient tongues struck therefrom arranged beneath the prongs when bent down, each tongue having a portion movable into position to obstruct the shifting movement of the compressor plate, when the prongs are interlocked with the compressor plate.

5. A paper fastener including a base plate having upwardly extending prongs for entering the papers to be fastened, a compressor plate having transverse guides coacting with the prongs, the prongs being bendable toward each other down on the compressor plate and the compressor plate having means along one of its longitudinal edges for interlocking with the bent down prongs upon shifting movement of the plate toward the prongs, after the prongs are bent down, and locking means including resilient tongues, each having a portion movable into position to obstruct the shifting movement of the compressor plate when the prongs are interlocked with the compressor plate, each of said tongues having a base portion underlying the adjacent prong when bent down onto the compressor plate and a narrower end portion movable into position behind the prong to obstruct movement of the compressor plate and prongs when the prongs are interlocked with the compressor plate.

6. A paper fastener including a base plate having upwardly extending prongs for entering papers to be fastened, a compressor plate having transverse guides coacting with the prongs, the prongs being bendable toward each other on the compressor plate and the compressor plate having means along its opposite longitudinal edges either of which interlocks with the bent down prongs upon shifting movement of the plate toward the prongs, after the prongs are bent down on the plate, and resilient means on the plate and pressing upwardly on the bent down prongs.

7. A paper fastener including a base plate having upwardly extending prongs for entering papers to be fastened, a compressor plate having transverse guides coacting with the prongs, the prongs being bendable toward each other on the compressor plate and the compressor plate having means along its opposite longitudinal edges either of which interlocks with the bent down prongs upon shifting movement of the plate toward the prongs, after the prongs are bent down on the plate, and resilient tongues struck from the base plate and arranged to create an upward

pressure on the bent down prongs when the prongs are interlocked with the base plate.

8. A paper fastener including a base plate having upwardly extending prongs for entering papers to be fastened, a compressor plate having transverse guides coacting with the prongs, the prongs being bendable toward each other on the compressor plate and the compressor plate having overhanging lips along its opposite longitudinal edges either of which interlocks with the

10

bent down prongs upon shifting movement of the plate toward the prongs, after the prongs are bent down on the plate, and resilient tongues struck from the base plate and arranged to create an upward pressure on the bent down prongs when the prongs are interlocked with either of the lips, said tongues having portions movable into interlocking engagement with the prongs when the prongs are interlocked with one of said lips.
